UNITED STATES PATENT OFFICE.

FRANK S. STIRTON, OF SPRINGFIELD, ONTARIO, CANADA.

AEROPLANE.

1,297,032.

Specification of Letters Patent. Patented Mar. 11, 1919.

Application filed July 28, 1915. Serial No. 42,463.

To all whom it may concern:

Be it known that I, FRANK STEWART STIRTON, a subject of the King of England, residing at Springfield, in the Province of Ontario, Dominion of Canada, have invented certain new and useful Improvements in Aeroplanes; and I do hereby declare the following to be a full, clear, and exact description of the invention, such as will enable others skilled in the art to which it applies to make and use the same.

This invention relates to an aeroplane.

An object of the invention resides in the provision of a biplane which will be propelled by a suitable propeller located in front of the main planes.

A further object of the invention resides in so constructing the main planes that they will assist in balancing the machine.

20 A further object of the invention resides in locating the elevating plane to the rear of the main planes and the operator's seat between the elevating plane and the main planes.

25 With these and other objects in view, such as will appear as the description progresses, my invention comprises the combination and arrangement of parts as set forth in and falling within the scope of the appended 30 claims.

Referring to the drawing:

Figure 1 is a plan view of my device.

Fig. 2 is a side elevation thereof.

Fig. 3 is a section on line 3-3 of Fig. 2.

35 Fig. 4 is a fragmental detail showing the relation of the jibs and ailerons to the main planes.

Fig. 5 is a fragmental detail of the elevating plane.

40 Fig. 6 is an enlarged detail of the steering mechanism.

Fig. 7 is a detail of the wheels and skids.

Fig. 8 is an enlarged side elevation of the steering mechanism.

45 Referring to the drawing wherein like parts are indicated by like characters throughout the several views:

In the embodiment of my invention shown in the drawing, I have disclosed a biplane 50 which consists of upper and lower planes 1 and 2, respectively, which are held in spaced relation by stanchions 3. Each of these planes is inclined upwardly from a point midway between its ends to the ends thereof as clearly shown in Fig. 2 of the drawing. The forming of these planes in this

manner adds greatly to the stability of the machine.

A frame is provided which consists of a pair of upper bars 4 and a pair of lower bars 5 which extend forwardly and rearwardly of the main planes and converge both forwardly and rearwardly. This frame is secured to certain of the intermediate stanchions 3 and is braced by suitable rectangular supports 6. Mounted on the forward end of this frame is a propeller 7 which is located in front of the main planes. Mounted on the rear end of the frame is an elevating plane 8 which is pivoted, as at 9, to the frame and is provided with a vertical plane 10 which extends above and below the said elevating plane. Between the ends of the main planes and pivotally mounted between two of the rear stanchions 3 are ailerons 11 which are movable on a horizontal pivot. Pivotally mounted on one of the stanchions 3 at each end of the main planes and at the forward side thereof is a vertically extending jib 12 which is in substantial alignment with the inner ends of the ailerons. These jibs are joined together by a bar 13 which extends from one to the other and is pivoted thereto at 14. These jibs extend between the main planes and slightly forwardly therefrom.

In order that the elevating plane 8 may be controlled from the operator's seat 15 which is located in the frame between the elevating plane and the main planes, I have provided a steering rod 16 which is pivoted on a support 17. Connected to the elevating plane 8, at 18, are wires 19 which extend forwardly and are secured to the steering rod 16 so that upon the forward or rearward movement of the steering rod the elevating plane will be raised or lowered. This steering rod is operable in a guide 20.

In order that the ailerons may be controlled, I have mounted pulleys 21 above the same on the main planes, over which pulleys controlling wires 23 extend which also extend over pulleys 24 on the intermediate stanchions 3. These wires extend around these pulleys and rearwardly and are connected to pedals 25 which are pivotally mounted on the support 17 and may be engaged by the feet of the operator and actuated to control the ailerons so that upon movement of the same the ailerons will be swung about their pivots, simultaneously. The axle of the pedals 25 passes through

the support 17 and serves as a pivot for the post 16 which vertically swings thereon.

Extending between and connected to the ailerons is a wire 23' which passes around 5 pulleys 22' so that when one aileron is raised the other will be lowered.

In order that the machine may be steered by controlling the movement of the jibs, I have connected wires 26 to the same which 10 extend around pulleys 27 on the intermediate stanchions, around pulleys 28 on the support 17 and around a steering wheel 29 on the upper end of the rod 16. Thus by turning the wheel the jibs may be turned 15 about their pivots, by turning the pedals the ailerons may be controlled and by moving the steering rod forwardly or rearwardly the elevating plane may be controlled.

In order that the machine may be supported when upon the ground and the shock 20 incident to the alighting absorbed, I have extended certain of the stanchions below the lowermost main plane 2 and have mounted on the ends thereof skids 30. On each side of 25 each of these skids is a wheel 31 which is resiliently mounted upon the skid by means of a coil spring 32 so that when the machine alights the springs will take up the shock. A similar skid 33 is mounted adjacent the 30 rear end of the frame and on each side of this skid is a wheel 34 which is mounted on the skid, resiliently, by means of a spring 35.

From the foregoing description it will be seen that I have located the propeller of the 35 machine in front of the main plane so that it will pull the machine through the air. I have also provided a vertical plane on the main elevating plane which will prevent the rear of the machine from skidding laterally, 40 and I have also provided ailerons for keeping the machine in lateral balance and for increasing the stability of the machine. Furthermore I have provided jibs by means of which the machine may be steered and I 45 have so located the operator's seat that it will be disposed to the rear of the main planes.

While I have illustrated and described a particular embodiment of my invention, I 50 have merely done so for the sake of convenience and I do not wish to be limited to that particular embodiment as it is obvious that numerous changes may be made within the details of construction thereof without in 55 any way departing from the spirit of the invention or exceeding the scope of the appended claims.

What I claim is:—

1. In a biplane, the combination with a 60 pair of spaced main planes, of a frame extending transversely thereof, an elevating

plane on the rear of said frame, ailerons and jibs disposed between the ends of the main planes, a support mounted on the frame, a vertically swinging steering post mounted 65 on the support, a steering wheel on the post, a pair of pedals on the support and forming a pivot for the post, wires extending from the elevating plane to the post and connected thereto, on opposite sides of its pivot, wires 70 extending from the ailerons to the pedals and additional controlling wires extending from the jibs to the said steering wheel.

2. In an aeroplane, a frame having upper and lower main planes, vertically swinging 75 ailerons supported between said main planes and projecting beyond the rear edges thereof, vertically swinging elevating planes at the other end of said frame, a vertical plane between the elevating planes, horizontally 80 movable jibs in said frame between the main planes, forwardly of and at the inner ends of the ailerons, and projected beyond the front ends of said main planes, and mechanism for operating the ailerons, elevating 85 planes, and jibs independently of each other.

3. In an aeroplane, a frame having sustaining planes, horizontally and vertically movable stabilizing planes between the sustaining planes, elevating planes on said 90 frame, a support in said frame, a vertically swinging post, pedals having an axle pivotally mounting the post on the support, a steering wheel mounted on the post and having a drum, a cable connected with the drum 95 and the vertical stabilizing planes, connections between the pedals and the horizontal stabilizing planes, and connections between the post on opposite sides of its pivot and the elevating planes.

4. An aeroplane including a frame having sustaining planes, horizontal and vertical stabilizing planes mounted between the sustaining planes, a support mounted on the frame, an arcuate guide carried by the support, a vertical pivoted lever mounted on the support and between the guides, pedals forming a part of the pivot of the lever, a steering wheel and drum mounted on the upper end of the lever, and cables connected 105 respectively to the drum and vertical stabilizing planes, to the pedals and horizontal stabilizing planes, an elevating plane at the rear of the frame, and cables connected to the lever and to the elevating plane.

In testimony whereof, I affix my signature, in the presence of two witnesses.

FRANK S. STIRTON.
